UNITED STATES PATENT OFFICE.

BANCROFT G. BRAINE, OF BROOKLYN, NEW YORK, ASSIGNOR TO THE RAIL JOINT COMPANY, OF NEW YORK, N. Y., A CORPORATION OF NEW YORK.

INSULATED RAIL-JOINT.

No. 895,839.

Specification of Letters Patent.

Patented Aug. 11, 1908.

Application filed May 24, 1907. Serial No. 375,509.

To all whom it may concern:

Be it known that I, BANCROFT G. BRAINE, a citizen of the United States, residing at Brooklyn, in the county of Queens and State 5 of New York, have invented certain new and useful Improvements in Insulated Rail-Joints, of which the following is a specification.

This invention relates to that class of insulated rail joints embodying a two part or sectional supporting base for the rail ends whereby a separate individual supporting base section is provided for each rail end, admitting of such a disposition of the insulation that there is no insulating material 10 which is required to carry the load or weight of the trains.

As a principal object, the invention has in view certain structural improvements in a joint of the character referred to intended to secure a satisfactory and effective reinforcement of the joint throughout. To this end the invention secures such a reinforcement of the side joint bars as to obtain a strengthening 25 of the joint at the center, thus resisting any tendency of the joint to give way or rupture at the weak point, viz: at the central point between the ties upon which the joint is supported.

Furthermore, the invention contemplates an improved construction providing what may be characterized as cushioning side bars or girders for the joint fastenings, and which serve to absorb lateral shocks and strains 35 imposed on the joint and joint fastenings, thereby more effectually maintaining the joint in a tightened condition.

A more general object of the invention is to improve the reinforcing and stiffening of 40 the joint while at the same time preserving the characteristic feature of providing each joint bar along one end portion thereof, with a short length base section which affords one rail end the support of the ties on both sides 45 of the meeting point of the rails, without contact with the corresponding base section carried by the other joint bar.

With these and many other objects in view, which will more readily appear as the 50 nature of the invention is better understood, the same consists in the novel construction, combination, and arrangement of parts hereinafter more fully described, illustrated, and claimed.

55 The essential features of the invention

above indicated are necessarily susceptible to a variety of structural modifications without departing from the scope thereof, but certain preferred embodiments of the invention are shown in the accompanying drawings, in 60 which—

Figure 1 is a perspective view of a rail joint, of the general Weber type, constructed in accordance with the present invention. Figs. 2 and 3 are separated perspective views, 65 respectively of the opposite shoe members of the joint. Fig. 4 is a bottom plan view of the joint. Figs. 5, 6, and 7 are cross sectional views, respectively on the lines 5—5, 6—6, and 7—7 of Fig. 4. Fig. 8 is a bottom 70 plan view of a modified form of joint embodying the present invention. Figs. 9, 10, and 11 are cross sectional views of the joint, respectively on the lines 9—9, 10—10, and 11—11 of Fig. 8. 75

Like references designate corresponding parts in the several figures of the drawings.

As indicated, the present invention is specially applicable to those types of insulated rail joints embodying a two-part supporting 80 base for the rail ends, and wherein each side joint bar or girder is provided along one end portion thereof with a short length base section affording a support for one rail end. Hence, various forms of insulated rail joints 85 involving said base construction may be provided with the special reinforcement claimed herein. This reinforcement may likewise be associated with side joint bars of various designs, irrespective of whether these joint bars 90 constitute the upright members of joint shoes or shoe angles, or are in the form of angle bars or splice bars arranged over the rail bases and disposed beneath the rail heads. However, certain practical embodiments of the invention are exemplified by 95 the type of joints shown in the drawings, and the latter will now be particularly referred to.

In the illustrated embodiment of the invention shown in the group of Figs. 1 to 7, inclusive of the drawings, the joint primarily embodies in its general organization the service rails 1 and 2, the opposite side joint bars 3 and 4, the wooden filler blocks 5 interposed between the side joint bars and the sides of the rails, and the usual series of joint bolts 6. In this joint, the side joint bars 3 and 4 are shown as constituting the upright members of shoe angles, and each of the same is provided along one end portion thereof with a 105 110

short length horizontal base section 7 affording one rail end the support of the ties on both sides of the meeting point of the rails 1 and 2, without contact with the corresponding base section of the other joint bar. In this particular, the joint bars 3 and 4 are of substantially the same design, and subserve practically the same functions as the corresponding members disclosed in a series of 10 companion applications, to-wit: filed November 8, 1906, Serial No. 342,523; filed November 8, 1906, Serial No. 342,524; filed December 6, 1906, Serial No. 346,643, and filed January 26, 1907, Serial No. 354,284, but a 15 distinguishing feature in the design and construction of the side joint bars in the present invention resides in the peculiar formation of these bars to secure an effective reinforcement thereof in a manner that strengthens 20 the joint at the center. This is accomplished by providing each side joint bar with what may be characterized as a supplemental upright reinforcing girder section designated by the reference character 8. 25 This reinforcing girder section 8 for each side joint bar is arranged in substantial parallelism to the latter, and in effect constitutes one of the wall sections of the joint bar itself, thus providing what may be termed a double 30 wall side bar, which, by reason of having its separate wall sections arranged in substantial parallelism, and united at one edge, as will be presently explained, has a cushioning effect or function in connection with the 35 joint fastenings. This cushioning function of each double-wall side bar operates to absorb lateral shocks and strains imposed on the joint and joint fastenings and thereby effectively maintains the joint in a tightened condition. 40

The supplemental upright reinforcing girder 8 of each side joint bar may be formed in various ways thereon in the process of manufacturing the latter, but one practical 45 and economical method of providing this construction is shown in the group of Figs. 1 to 7, inclusive, and consists in utilizing, in each bar, that portion of the base piece which is cut out to leave the individual rail supporting base sections 7 along one end portion 50 of the bar. In other words, in this method of construction, that portion of the base which is cut from the end portion of the bar having no rail supporting base section, may be bent or folded upward alongside of the 55 main upright portion of the side bar to provide the said reinforcing girder section 8. In this way the material is fully economized besides producing the double-wall side bars 60 which are thus greatly reinforced, and particularly provide for a strengthening of the joint at the center. Furthermore, in forming the upright girder sections 8, by bending the same upward from a section of the base 65 piece of the bar, the girder section of each

bar is doubled upon the latter from a bend or bight 9 at one of the longitudinal edges of the bar, and in the design of joint being described, this bend or bight 9 occurs at the lower or bottom edge of the side bar, as may 70 be plainly seen from Figs. 5, 6 and 7 of the drawings. In this connection, it will also be observed that the bending or folding of the girder section 8 into upright position provides for a relative spring action between the 75 girder section 8 and the joint bar proper, which spring action secures the cushioning effect above referred to.

In addition to the reinforcement necessarily provided at the bottom edges of the 80 side joint bars by the bends or bights 9, each of said joint bars may be further provided at their bottom edges with the reinforcing foot flanges 10 which may also be utilized for the usual spiking purposes. Another feature to 85 observe in connection with the special reinforcement described, is that it may be necessary to provide only one end portion of each side joint bar with the supplemental girder section 8, preferably that end portion 90 having no rail supporting base or base section as shown in the entire group of Figs. 1 to 7, inclusive of the drawings. However, a modification of the above idea is suggested in the group of Figs. 8 to 11, inclusive of the 95 drawings. This modification not only involves the feature of constructing each side bar with a double wall or upright girder reinforcement throughout its entire length, and hence throughout the entire length of 100 the joint, but also presents the idea of making the opposite shoe members from bent plates in which the supplemental upright reinforcing girder sections 8 are bent downwardly, at the bends or bights 11, from the 105 top edges of the joint bar proper. In other respects, the modification shown in Figs. 8 to 11, inclusive of the drawings, is the same in construction and effect as the joint illustrated in Figs. 1 to 7, inclusive of the drawings, so similar reference characters will apply to similar parts in the said separate groups of figures.

In both forms of joint described, any suitable insulating expedients may be utilized to 115 complete the insulation thereof, such for instance as the insulating end post 12 interposed between the rail ends and extended at its base to lie between the separate supporting base sections 7—7, and insulating sleeves 120 or bushings arranged in the holes in the rail webs and receiving the joint bolts therethrough. These insulating features, however, may be varied without in any way affecting the present invention, and it will also be understood that various other modifications in the structure claimed may be resort 125 ed to without departing from the spirit or sacrificing any of the advantages of the invention.

I claim:

1. In an insulated rail joint, the service rails, opposite joint bars each of which is provided with a base section and with an upright supplemental girder section extending beyond said base section, and insulating means.

2. In an insulated rail joint, the service rails, side joint bars each of which is provided with an upright double wall and with a short length base plate affording a support for one rail end, and insulating means.

3. In an insulated rail joint, the service

rails, side joint bars each of which is provided along one end portion with a short 15 length base section affording a support for one rail end, and with an upright double wall extending along that end portion of the bar having no rail supporting base section, and insulating means.

In testimony whereof I hereunto affix my signature in the presence of two witnesses.

BANCROFT G. BRAINE.
